CLAIM

The ornamental design for a handheld multi-modal imaging device, as shown and described.

DESCRIPTION

FIG. 1 is a top, left side perspective view of a first embodiment of a handheld multi-modal imaging device showing our new design.

FIG. 2 is a bottom, left side perspective view thereof.

FIG. 3 is a left side view thereof.

FIG. 4 is a right side view thereof.

FIG. 5 is a top view thereof.

FIG. 6 is a bottom view thereof.

FIG. 7 is a front view thereof.

FIG. 8 is a back view thereof.

FIG. 9 is a top, left side perspective view of a second embodiment of a handheld multi-modal imaging device showing our new design.

FIG. 10 is a bottom, left side perspective view thereof.

FIG. 11 is a left side view thereof.

FIG. 12 is a right side view thereof.

FIG. 13 is a top view thereof.

FIG. 14 is a bottom view thereof.

FIG. 15 is a front view thereof; and,

FIG. 16 is a back view thereof.

The broken lines on the handle member represent environment and the remaining broken lines illustrate portions of the handheld multi-modal imaging device that form no part of the claimed design.

The handheld multi-modal imaging device is shown with a symbolic break in its length. The appearance of any portion of the article between the break lines forms no part of the claimed design.
